UNITED STATES PATENT OFFICE.

WALTER LANE, OF CHICAGO, ILLINOIS, ASSIGNOR TO BUSH AND LANE
PIANO CO., OF CHICAGO, ILLINOIS, A CORPORATION OF ILLINOIS.

DESIGN FOR A PIANO-CASE.

No. 37,573.

Specification for Design.

Patented Oct. 10, 1905.

Application filed August 16, 1905. Serial No. 274,476. Term of patent 7 years.

To all whom it may concern:

Be it known that I, WALTER LANE, a citizen of the United States, residing at Chicago, in the county of Cook and State of Illinois, have invented a new, original, and ornamental Design for Piano-Cases, of which the following is a specification, reference being had to the accompanying drawing, forming a part hereof.

The figure is a perspective view showing my new design.

I claim—

The ornamental design for a piano-case, as shown.

WALTER LANE.
